UNITED STATES PATENT OFFICE.

ROBERT GOOD, JR., OF CLARKSBURG, WEST VIRGINIA, ASSIGNOR TO HAZEL-ATLAS GLASS COMPANY, OF WHEELING, WEST VIRGINIA, A CORPORATION OF WEST VIRGINIA.

MACHINERY FOR MANUFACTURING GLASSWARE.

SPECIFICATION forming part of Letters Patent No. 767,935, dated August 16, 1904.

Application filed June 8, 1903. Serial No. 160,603. (No model.)

To all whom it may concern:

Be it known that I, ROBERT GOOD, Jr., a citizen of the United States, residing at Clarksburg, in the county of Harrison and State of West Virginia, have invented or discovered certain new and useful Improvements in Machinery for the Manufacture of Glassware, of which improvements the following is a specification.

10 My invention relates to machinery for the manufacture of glassware; and it consists in the construction and arrangement of mechanism hereinafter described and claimed.

In the accompanying drawings, forming a part of this specification, I have illustrated my invention embodied in a machine for the manufacture of hollow articles of glassware by the well-known pressing and blowing process wherein a mass of molten glass is first pressed 15 to a preliminary shape and the body of the pressed blank then blown to finished form. The machine is practically automatic in its action, is of strong and durable construction, and has a large productive capacity of articles 20 of superior quality at a very small expense for operation and repairs.

The general organization and operation of this machine, which I here show and describe as the preferable embodiment of my invention, 25 is, briefly stated, as follows: The pressing-plunger is provided with a passage through it connected with a supply of air under pressure, so that it may also serve as a blowpipe. By the use of this type of plunger I can more conveniently both press and blow the glass at a common operating-point, and thus dispense with the operation of transferring the pressed blank from the point where it has been pressed to another blowing-point more or less distant 30 therefrom. The passage of the air through the plunger also materially contributes to keeping the latter at the proper temperature, and I have in this respect also found it more satisfactory than the water-cooled plungers now 35 commonly used. The form of plunger employed is, however, not an essential part of my invention, since a separate blowing member may be employed, if desired. I have illus-

trated and prefer to use such a plunger as is shown and described in United States Letters 50 Patent No. 585,469.

Below the plunger is mounted the mold-support or table, which in its preferred form, as herein illustrated, is rectangular and is reciprocated lengthwise. Upon the table are mounted a sectional blank or press mold and a plurality of sectional finishing or blow molds. I prefer to use two blow-molds, and I have herein shown such blow-molds arranged one on each side of the press-mold, so that by the reciprocation of the table first the press-mold and one of the blow-molds and then the press-mold and the other blow-mold may be carried in succession into position under the pressing and blowing member. Suitable mechanism, 55 to be hereinafter described, is employed for moving the mold-support intermittently in two successive steps in each direction, the mold-support being stopped as each mold is brought under the pressing and blowing member for a time sufficient to permit the operation of the latter upon the glass in the mold. 60

A sectional neck-mold is suitably arranged to be closed upon the press-mold when the latter is in position under the plunger. When 75 the blank has been pressed, the press-mold is automatically opened and is carried away by the movement of the mold-support, leaving the pressed blank suspended *in situ* in the neck-mold in the path of the approaching 80 open blow-mold. The blow-mold is then closed about the blank, the blank blown to finished form, the neck-mold opened, and the mold-support moved in the reverse direction to return the press-mold, with a fresh charge 85 of glass, into position under the plunger. The neck-mold is again closed, another blank pressed, the mold-support moved another step, and the other blow-mold closed about the second blank. The first blow-mold being then 90 at the outer limit of its travel, it is opened to discharge its finished article, and the second blank having meanwhile been blown and the press-mold closed and charged the machine is ready for a new cycle of operations. The 95 press-mold is thus employed in the formation

of the pressed blank for each article which is made, while the blow-molds are used alternately.

Since in the arrangement of molds above 5 described the press-mold is to be alternately charged on opposite sides of the operating-point, I arrange on each side and immediately above the initial position of the press-mold a cutter, to be hereinafter described, for cutting the molten glass from the gathering-iron as the latter is held over the press-mold.

As the gatherer drops the glass into the press-mold he depresses a treadle, which by its initial movement operates the cutter to 15 cut off the glass and then sets the machine in motion. When the pressed blank has been blown and the neck-mold opened, the machine is automatically stopped. The gatherer then charges the press-mold on the other side of 20 the plunger and starts the machine again, and the reverse movement of the mold-support to produce another article takes place.

In the accompanying drawings, in which the same numerals are employed to designate the 25 same parts in each figure, Figure 1, Sheet 1, is a front elevation of the machine with the mold-support at the right-hand limit of its movement. Fig. 2, Sheet 2, is a sectional elevation through the center of the machine, the 30 mold-support being shown standing at the left-hand limit of its movement, a finished article inclosed in the right-hand blow-mold under the pressing and blowing member, the press-mold standing closed under the cutter 35 ready to receive its charge of molten glass, and the left-hand blow-mold open. In this figure the cam-track for moving the mold-support is shown in elevation. Fig. 3, Sheet 3, is a transverse sectional elevation at right 40 angles to that of Fig. 2, showing the press-mold, with its charge of molten glass, in position under the plunger. Fig. 3^a, Sheet 3, is a fragmentary sectional elevation of the treadle and its associated parts, showing the 45 treadle elevated. Fig. 4, Sheet 4, is a side elevation of the machine, showing the press-mold under the plunger, as in Fig. 3, and the plunger depressed. Fig. 5, Sheet 5, is a horizontal section, partly in plan, on the 50 line *a a* of Fig. 1. Fig. 6, Sheet 6, is a horizontal section, partly in plan, on the line *b b* of Fig. 2. Fig. 7, Sheet 6, is a plan view of the mold-bed, partly in section, standing in the same position as in Figs. 2 and 6. Fig. 55 8, Sheet 7, is a transverse vertical section through one of the finishing-molds and its associated parts on the line *c c* of Fig. 2. Fig. 9, Sheet 7, is an elevation, partly in section, showing the treadle mechanism and cams for 60 operating the plunger and opening the press-mold. Fig. 10, Sheet 7, is a detail view showing the plunger-operating cam and lever. Fig. 11, Sheet 7, is an enlarged sectional elevation illustrating the means for holding the 65 neck-mold in its elevated or its lowered posi-

tion. Fig. 12, Sheet 8, is a sectional elevation, partly broken away, on the line *d d* of Fig. 2, showing the cam and its connected levers for operating the neck-mold. Figs. 13, 14, 15, 16, 17, 18, 19, and 20, Sheet 8, are detail views of the cutters and their connected mechanism, Fig. 16 being a sectional elevation of one of the cutters on the line *e e* of Fig. 15 and Fig. 19 being a sectional view of one of the knives on the line *f f* of Fig. 18. Figs. 16, 19, and 20 are on an enlarged scale. Fig. 21, Sheet 5, is a plan view showing the cam for closing the press-mold. Fig. 22, Sheet 5, is a section showing the air-valve-operating means on the line *g g* of Fig. 5 looking toward the front of the machine. Fig. 23, Sheet 5, is a section on the line *h h* of Fig. 22. Fig. 24, Sheet 5, is an enlarged section through the valve. Fig. 25, Sheet 2, is a detached view of the bottom-tilting mechanism. 85

1 represents the main frame of the machine, which may be of any suitable construction. On the top of the frame are tracks or ways 2 for the mold-support or table 3, the latter being shown as provided with depending flanges 90 4, the lower edges of which rest upon roller-carriages 5, which run in the ways 2, Figs. 2, 3, 4, 6, and 7. In order to more effectually secure the table against lateral displacement, I prefer to provide it also with depending 95 studs 6, carrying rollers which bear against the side walls of a longitudinal opening 7 in the top of the frame, Figs. 3 and 4.

8 represents the press-mold, which in the present machine is mounted substantially 100 centrally of the table, and 9 and 9^a respectively represent the two blow-molds, in this case mounted one on each side of the press-mold 8. Each of the molds is shown as formed of two separate body-sections movable toward and from each other in transverse ways 10 on the table, the mold-sections being fastened to carriages 11, which slide in the ways and are held therein by overhanging plates 11^a. (See Figs. 2, 3, 7, and 8.) 110

12 represents a press-frame arranged above the table and molds and supported by brackets or standards 13, rising from the main frame on each side of the table. 14 represents the pressing-plunger, which, as already stated, is 115 in the present machine adapted to also serve as a blowpipe. For that purpose I prefer to use such a plunger as is illustrated and described in Letters Patent No. 585,469, dated June 29, 1897, and is herein shown (see Fig. 3) as provided with an interior passage having communication at the top with a source of fluid under pressure and closed at the point of the plunger by a valve 15. The stem 16 of this valve passes upwardly through the passage 120 and is provided at its top with a nut 17. Between the nut 17 and the top of the shank or extension of the plunger is confined a small spring 18, the tension of which is sufficient to hold the valve 15 normally closed. When, 130

however, fluid under pressure is admitted to the plunger, it easily overcomes the tension of the spring 18 and opens the valve 15.

The plunger 14 is carried by a cross-head 19, vertically movable on upright guides or columns 20, rising from the press-frame 12. The plunger is shown as arranged centrally over the main frame and is guided at its lower end in an opening 21 in the press-frame. (See Figs. 2 and 3.) It is preferably adjustably secured to the cross-head 19 by any suitable means, and for this purpose I have shown it as provided with an upper screw-threaded shank 22, screwed into a threaded opening in the cross-head and held therein by jam-nuts 23. I have also provided guide-bars 24, secured to the plunger and extending upwardly into vertical openings in the cross-head. (See Fig. 3.) The cross-head is also preferably provided with an upwardly-extending guide-rod 25, which slides in an opening in a cross-piece 26, fixed to the upper ends of the stationary columns 20.

For the purpose of moving the mold-support or table 3 I employ a cam-shaft 27, arranged longitudinally beneath the table and journaled at its ends in suitable bearings in the ends of the main frame. Secured to the cam-shaft 27, as by a drum 28 or other suitable means, is a continuous cam-track, which I have shown as extending completely around the drum and substantially from end to end thereof. (See Figs. 2, 3, and 5.) This cam-track is provided at its opposite ends with short straight portions 29, which are arranged substantially on diametrically opposite sides of the drum and shaft, and substantially midway between these straight end portions and at an angle of about ninety degrees or the 40 distance of a quarter-turn therefrom are arranged two other opposite short straight portions 30. Connecting the end portions 29 with these intermediate portions 30, so as to form of the whole a single continuous circumferential track, are four oblique portions 31. Depending from the table, substantially centrally thereof, is a stud 32, the lower end of which, preferably provided with a roller, engages the cam-track. (See Figs. 2, 3, 5, and 6.) It is thus apparent that in a quarter-revolution of the cam-track the stud 32 on the table will pass from one of the straight portions along one of the oblique portions 31 to the next straight portion, thus causing the table to move one step 55 in its traverse, which is a distance equal to that between the center of one of the blow-molds and the center of the press-mold. Thus, starting with the table at its left-hand limit, as shown in Fig. 2, the stud 32 will pass from the left-hand straight end portion 29 along the oblique portion 31 on the back of the drum to the next intermediate straight portion 30, thereby carrying the press-mold into position under the plunger and correspondingly moving the two blow-molds. The revolu-

tion of the cam-shaft and drum continuing, the stud 32 will remain in the intermediate straight portion long enough to permit the operation of the plunger, (and movements of other mechanism to be hereinafter described,) 70 after which, passing into the next succeeding oblique portion, it will move along to the straight end portion opposite that from which it started, (the press-mold having been first opened and the pressed glass blank left suspended under the plunger by means to be hereinafter described,) thus moving the press-mold onward to the opposite side of the plunger and the left-hand blow-mold of Fig. 2 into position under the plunger, where it is 80 closed about the blank and the blowing operation performed. The machine is then automatically stopped. When it is again started, the direction of movement of the table is reversed, the stud 32 traversing the cam-track 85 back to its original starting-point, and thus carrying first the press-mold and then the right-hand blow-mold successively into position under the plunger. By one revolution of the cam-shaft 27 and drum 28, therefore, 90 the table is moved from its extreme position at one end of the machine, as shown in Fig. 2, to carry the press-mold into position under the plunger, hold it there for a period, then in the same direction to carry the left-hand blow-mold to the same operating-point 95 and hold it there until the blank has been blown and the press-mold again charged. The movement of the table is then reversed to carry the press-mold again into position under the plunger, hold it there for a period, and then carry the right-hand blow-mold to the operating-point, the press-mold and the left-hand blow-mold being returned to their initial positions. 105

Any suitable mechanism may be employed for operating the plunger; but I prefer and have illustrated mechanism substantially like that described in Letters Patent No. 674,378, dated May 21, 1901. Referring first to Figs. 3 and 4, 33 indicates a bent lever, one arm of which, preferably bifurcated, is pivoted at its end to the stationary cross-piece 26 at the top of the machine, and to the other arm is attached a rod 34, carrying a weight 35, which is preferably adjustable on the rod by means of a screw-thread, as shown. The elbow of the lever 33 is connected by links 36 to the movable cross-head 19 of the plunger, and the free end of its weight-carrying arm is connected 110 by a link 37 with one end of a lever 38, which is fulcrumed intermediate of its ends at one side of the stationary press-frame 12. The lower end of this lever 38 is connected by a link 39 (which is preferably made adjustable 115 in length by a turnbuckle 40) with the end of an arm 41. This arm is secured to one end of a sleeve 42, (see Figs. 5 and 10,) loosely mounted upon a counter-shaft 43, which is journaled in the ends of the main frame 1 and 120

lies parallel with the cam-shaft 27. Secured to the opposite end of the sleeve 42 is an arm 44, which is provided at its end with a roller which bears on the periphery of a cam 45, 5 shown as formed on the end of the drum 28. The cam 45, as shown in Fig. 10, is made up of two circumferential flanges 46 and cam-flanges 47, extending from the front end of each circumferential flange inwardly toward the cam-shaft 27. The rear end of each circumferential flange terminates short of the radial cam-flange of the other circumferential flange, so as to leave a space into which the roller and arm 44 can enter. Supposing the 10 cam to rotate from left to right, as indicated by the arrow in Fig. 10, the roller on the end of the arm 44 will ride on the circumferential flange 46 until the rear end of the latter passes the roller. When the latter occurs, the roller 15 and arm 44 will move inwardly, thereby withdrawing support from the weighted lever 33 at the top of the machine. The lever 33 will therefore drop, as shown in Fig. 4, and the plunger cross-head 19 and plunger be forced 20 down by the straightening of the toggle formed by the lever 33 and links 36. The cam 45, continuing to rotate in the direction stated, will cause one of the radial flanges 47 to engage the roller on the end of the arm 44 25 and force the same outwardly onto the other advancing circumferential flange, thus elevating the arm 44, depressing the arm 41, and through the described connections, Fig. 3, 30 elevating the weighted lever 33 and withdrawing 35 the plunger from the mold.

In the present machine I provide a cutting mechanism on each side of the plunger over the respective initial positions of the press-mold for severing the charge of molten glass 40 from the gathering-iron. Each such cutting mechanism is provided with two coöperating blades.

48 and 48^a represent two cutter-frames, one on each side of the plunger. These cutter-frames are carried by rockers 49, which extend through openings in the press-frame 12 and are fixed to horizontal pivot-pins 50, journaled in the press-frame, so as to have a slight vertical movement in reverse of each other—50 that is, when one cutter-frame is lowered the other is raised, and vice versa. (See Figs. 2, 3, 14, 15, and 18.) Each cutter-frame is preferably adjustably secured to the rockers by means of screw-threaded stems 51, secured to 55 the cutter-frame and passing through openings in the ends of the rockers, to which they are secured by jam-nuts. (See Figs. 14 and 18.) The rocking movement of the cutter-frames is so timed that each is lowered into 60 position immediately over the press-mold and remains in this position until the blow-mold containing the finished vessel has passed from under the cutter-frame on the opposite side, so that such opposite cutter-frame may stand 65 clear of the neck of the finished vessel.

52 and 52^a represent two shafts (see Figs. 3, 4, 13, and 14) which are journaled parallel with each other between the upper separated sides of the press-frame 12. One of these shafts, as 52, is provided at its outer end with 70 a bell-crank lever 53, one arm of which is connected by a link 54 to an arm 55 on the adjacent shaft 52^a, while the other arm of this bell-crank lever (see Fig. 13) is connected by a link 56 to one arm of a bell-crank lever 57, 75 pivoted on a bracket on the press-frame 12. The other arm of this bell-crank lever 57 hangs beside the table 3 in the path of two studs or projections 58 on the edge of the latter, (see Figs. 4 and 7,) one at or near each end. When 80 in the movement of the table 3 either of said projections 58 is brought into engagement with the free end of bell-crank lever 57, the latter is oscillated, and through the described connections the shafts 52 and 52^a are correspondingly oscillated.

The shafts 52 and 52^a each carry on their inner ends spurs 59, and between these spurs projects an arm 60, secured to one of the pivot-pins of the rockers of the cutter-frames. 90 (See Figs. 3, 14, and 20.) When the shafts 52 and 52^a are oscillated in one direction by the projection 58 on one end of the table 3, the spurs 59 will act on the arm 60 to rotate the pivot-pins to lower one of the cutter-frames and raise the other, in which position they will remain until the corresponding projection 58 on the other end of the table 95 causes their reverse movement.

Each cutter-frame carries a pair of superposed blades 61 and 61^a, movable toward and from each other longitudinally of the cutter-frame. These blades are caused to move simultaneously and are provided with coöperating notched cutting edges, which are substantially V-shaped, as shown in Fig. 17. I have found this construction of the blades to be of material advantage, since the cut is made evenly and cleanly, the glass falling properly into the mold without any tendency to throw the end of the gather to one side, as is caused by the dragging action of the pivoted shear-like cutters which have been generally employed in manually cutting off the gather. Immediately above the diamond-shaped opening 110 between the blades is an opening 62 in the cutter-frame, through which the gather falls from the gathering-iron. 115

The blades are carried by slide-bars 63 and 63^a, which slide in grooves or ways on the under side of the cutter-frame. (See Figs. 16 and 19.) The blade 61 is loosely carried by its slide-bar 63 by means of depending headed pins 64, secured to the slide-bar and passing through holes in the blade. This upper blade 61 is held down yieldingly upon the lower blade 61^a by means of leaf-springs 65, located between said upper blade and the cutter-frame and secured to the latter. The simultaneous movement of the two blades in op- 125 130

posite directions toward and from each other may be accomplished by any suitable means, for instance, as shown by a rod 66, secured rigidly to one blade, extending longitudinally in guides at one side of the cutter-frame and loosely connected at its free end to one end of a lever 67, pivoted on the cutter-frame, the opposite end of said lever 67 being loosely connected to the slide-bar of the other blade.

For operating the blades to cut off the gather any suitable mechanism may be employed, and I have shown herein such mechanism operated by the gatherer by means of a treadle 68, Figs. 3, 3^a, 4, and 5. The treadle 68 is arranged at the front of the main frame and is secured to a rock-shaft 69, Figs. 3 and 5. The shaft 69 is provided with an arm 70, carrying a weight 71, Figs. 4 and 5, which tends to hold the treadle in elevated position.

On the treadle is mounted an upwardly-extending arm 72, arranged beneath a weighted bell-crank lever 73, pivoted on the front of the main frame. This lever 73 is provided with a depending arm 74, pivoted at its upper end to the lever, so as to stand in the path of movement of the arm 72 of the treadle, as shown in Fig. 3^a. The depending arm 74 is provided with a shoulder 75, by which when swung forwardly and upwardly by the treadle-arm it will bear against and raise the weighted arm of the lever 73, while its pivotal connection to the lever enables it to be swung out of the way to allow the treadle-arm to return to its original position when the treadle is elevated. The depending arm 74 is preferably composed of two pieces arranged side by side and carrying between their lower ends a roller 76 for engagement with the treadle-arm. The weighted arm of the lever 73 is connected by links 77, Fig. 4, to the forwardly-projecting arms of two bell-crank levers 78, pivoted on opposite sides of the front supporting-bracket 13 of the press-frame. The other arms of the bell-crank levers 78 are connected to two inwardly-extending operating-bars 79, suspended by links 80, respectively, from studs 81 on opposite sides of the press-frame 12. The inner end of each of the operating-bars 79 is provided with a vertically-elongated slot 50 or eye 82, lying adjacent to the rod 66 of the adjacent cutter-frame. Secured to each rod 66 is a laterally-projecting finger 83. (See Fig. 18.) When one of the cutter-frames is down in operative position, the finger 83 of its rod 66 projects into the vertically-elongated slot 82 in the end of the adjacent operating-bar 79, as shown at the right-hand side of Fig. 18, so that movement of the bar 79 will cause a corresponding movement of the rod 66 and so operate the blades of the cutter. When either cutter-frame is elevated out of its operative position, the finger 83 of its rod 66 is withdrawn from the slot 82, as shown at the left-hand side of Fig. 18, and conse-

quently its blades are not then operated by the movement of its adjacent bar 79.

When the operator depresses the treadle 68, the forward movement of its arm 72 swings the pivoted arm 74 forwardly and the weighted arm of lever 73 upwardly, whereby the operating-bars 79 are moved inwardly, thereby closing the blades of the operating-cutter and cutting off the gather. When this has been accomplished, the treadle-arm 72 has passed the depending arm 74 and the weighted arm of lever 73 drops, thereby opening the knives. When the treadle is released, its arm 72 will swing back and pass the depending pivoted arm 74, which will then drop back into place. A cushion 84, of rawhide or like material, is preferably mounted on the front of the main frame (see Fig. 3) to deaden the impact of the inner arm of lever 73.

To coöperate with the press-mold and form the neck of the article as well as to support the pressed blank when the press-mold is opened and closed at the operating-point immediately under the plunger. This neck-mold comprises two sections, which I have shown as slidably mounted on the under side of a frame 86 and movable toward and from each other. The frame 86 is provided with a central opening containing the plunger-ring 87, which is of any suitable construction and serves to complete the mold between the neck-mold and the plunger, as shown in Figs. 2 and 3.

The frame 86 is given a slight vertical movement into and out of operative position and for that purpose, as well as for opening and closing the neck-mold, I preferably make use of mechanism arranged and operating as follows: 88 represents levers arranged at opposite ends of the frame 86 and each pivoted between a pair of posts 89, mounted on said frame at its opposite ends, Figs. 3 and 11. The inner depending arms of the levers 88 extend down through openings in the frame and are loosely connected to the neck-mold sections as by extending into openings in the latter. The other arm of each lever 88 projects outwardly between two plates 90, Fig. 11, secured to the adjacent pivot-posts 89 and extending upwardly between the sides of the press-frame 12. Each of the plates 90 is provided with a roller, which bears against the adjacent inner face of the press-frame and is adapted to roll vertically thereon. The upper ends of the plates 90 are reduced, so as to form spring-shanks 91, and are connected together. The action of the spring-shanks is to hold the plates 90 outwardly and cause their rollers to bear with considerable friction against the inner faces of the sides of the

press-frame, so as to hold the neck-mold frame 86 in the position to which it is moved. The pressure of the spring-shanks 91 is preferably made adjustable by means of a block 92, located between the converging shanks and adjustable by a set-screw 93. The neck-mold frame 86 is provided with vertical guide-rods 94, extending upwardly through guide-bearings on the walls of the press-frame.

10 When the outer ends of the levers 88 are moved downwardly, they first act to slide the sections of the neck-mold 85 together, and then by their continued downward movement cause the neck-mold frame 86 to move bodily downward into operative position. When the levers 88 are moved upwardly, they act to first separate the neck-mold sections and then move the neck-mold frame bodily upward, the latter being then held in elevated position by

15 means of the friction devices described.

The outer ends of the levers 88 are connected by links 95 (preferably made adjustable in length by turnbuckles, so as to make the neck-mold adjustable to the height of the article to be made) to arms 96 of the horizontal rock-shafts 97, (see Fig. 3,) mounted on opposite sides of the main frame. On the end face of the drum 28, opposite to that shown in Figs. 9 and 10, (see Fig. 12,) is a cam-track 20 made up of diametrically opposite salient cam portions 98, connected by concentric portions 99. To the rock-shafts 97, adjacent to this end of the drum, are secured the arms 100, connected by links 101 to levers 102, arranged beside the cam-track on opposite sides of its center and pivoted at their lower ends to studs on the end wall of the main frame, Figs. 2 and 12. Each of the levers 102 is provided with a roller 103, engaging the cam-track.

When the rotation of the drum 28 causes the rollers 103 to move inwardly into the portions 99 of the cam-track, the levers 102 are drawn toward one another, thereby rocking the shafts 97 and drawing the levers 88 downwardly, thereby first closing the neck-mold sections and then moving the neck-mold frame and the neck-mold bodily downward onto the press-mold.

50 As has been hereinbefore stated, I employ the neck-mold to support the pressed blank after the press-mold has been opened and until the blowing has been accomplished. The rollers 103 will then enter the portions 98 of the cam-track, thereby moving the levers 102 away from each other and through the described connections first open the neck-mold and then lift it bodily from the blow-mold. The machine is then automatically stopped by 55 mechanism to be hereinafter described.

Any suitable means may be employed for opening the press-mold to disengage the pressed blank, and I have shown in the accompanying drawings one arrangement of 60 mechanism well adapted for that purpose.

On the drum 28 at diametrically opposite points are arranged two projections 104, and in the path of said projections and on opposite sides of the drum are the ends of two levers 105, pivoted on brackets on the main frame, 70 the upper ends of which normally rest against the sides of the main frame. (See Fig. 3.) Journaled in suitable bearings depending from the ends of the table 3 and at opposite sides thereof are horizontal shafts 106, and loosely 75 mounted on said shafts on opposite sides of the press-mold are the bell-crank levers 107, the lower arms 108 of which hang downwardly. The other inwardly-extending arms 109 of these levers are connected by links 110, which 80 extend upwardly through suitable slots in the table, with rock-arms 111 loosely mounted upon horizontal shafts 112, journaled at the front and rear ends of the table in upwardly-projecting bearing-brackets. The rock-arms 85 111 project toward the adjacent press-mold sections and are respectively connected to such opposite sections by links 113. The links 113 and rock-arms 111 constitute toggles and serve when extended to firmly hold the press-mold sections in closed relation. When the 90 table 3 is at the center of its range of movement, with the press-mold under the plunger, the ends of depending arms 108 of levers 107 will lie respectively inside and in the line of 95 movement of the upper ends of the levers 105. Immediately after the plunger has been retracted from the press-mold the opposite projections 104 on the drum 28 will strike the lower ends of levers 105, throwing the lower ends 100 of said levers outwardly and their upper ends inwardly against the depending arms 108 of levers 107, and thereby through the described connections draw the press-mold sections apart to disengage the pressed blank. The levers 105 return by gravity to their normal position, and with the next movement of the table the press-mold is again closed by mechanism preferably constructed and operated as follows: 110 114, Figs. 3 and 21, represents a pair of cam-plates suitably secured to the opposite sides of the main frame below the table and longitudinally thereof. Each cam-plate is of concave form, being curved in an arc concentric with the axis of the adjacent lever 107, and is 115 provided with a central slot 115, extending from the outer toward the inner side thereof, in which works the upper end of the adjacent lever 105. The upper curved face of each cam-plate is provided with a curved cam-groove 116, the ends of which coincide with the limits of movement of the press-mold and the levers 107, and a straight groove 117 connects the ends of the curved groove. The 120 end of the depending arm 108 of the adjacent bell-crank lever 107, which is preferably provided with an antifriction-roller, rests in said grooves and travels therein with the movement of the table. When the press-mold is in position under the plunger, the end of de- 125

pendent arm 108 lies in the center of the straight groove 117 (coinciding with the slot 115) and immediately in front of the upper end of lever 105, resting in the outer end of said slot. As above explained, immediately after the plunger has been withdrawn from the press-mold the opposite projections 104 on the drum 28 oscillate the opposite levers 105 to move the upper ends of said levers inwardly, and the latter throw the ends of the depending arms 108 inwardly and upwardly along the slot 115 to the center of the curved grooves 116. Immediately after the press-mold has been thus opened the movement of the table commences, and the ends of the arms 108 are caused to move in the curved grooves 116 gradually back to the ends of the straight grooves, thereby effecting the closure of the press-mold when the table has again come to a stop with the press-mold under one of the cutters. Then when the movement of the table is reversed to bring the press-mold again under the plunger the ends of the arms 108 travel in the straight grooves 117 until the press-mold is in position and they again rest in the slots 115 immediately in front of the ends of levers 105.

For closing the blow-mold about the pressed blank any suitable mechanism arranged to be operated at the proper time may be employed; that which I believe to be best adapted to the machine herein described being substantially as follows: 118 and 118^a, Figs. 2 and 6, represent two transverse shafts suitably mounted in bearings depending from the table on opposite sides thereof, said shafts being arranged, respectively, near the opposite ends of the table. These transverse shafts are geared to the lower longitudinal shafts 106 by bevel-pinions 119 at the ends of said transverse shafts meshing with bevel-pinions 120, secured to said longitudinal shafts, Fig. 6. The lower longitudinal shafts 106 are respectively connected by rock-arms 121 and links 122 with rock-arms upon the upper longitudinal shafts 112. Each of the shafts 112 is provided with two rock-arms 123 and 124, the arms 123 on each shaft being adjacent and connected to the opposite sections of the blow-mold 9, and the arms 124 on each shaft being adjacent and connected to the opposite sections of the blow-mold 9^a, such connections being made by links 125, so that, as in the case of the press-mold, said rock-arms and links form toggles for firmly closing the molds. (See Figs. 7 and 8.) The rock-arms 123 and 124 on each shaft 112 are arranged at angles to each other, so that when the shafts 112 are rocked to close one of the blow-molds the other blow-mold will be opened by the same movement—that is, the blow-molds are opened and closed in reverse.

Each of the transverse shafts 118 and 118^a is provided with a depending tappet-arm 126, and at the opposite ends of the machine are

bent levers 127, pivoted to the main frame, the upper ends of which, preferably provided with a roller, lie in line with the respective tappet-arms 126. (See Figs. 1 and 2.) The opposite ends of said levers 127 are also provided with rollers which rest upon cam-disks 128, mounted on opposite ends of the shaft 27. Each of these disks has a cam projection adapted to pass under and oscillate its lever 127 when the table reaches the limit of its travel in that direction, thereby causing the upper end of said lever 127 to engage and tip its tappet-arm 126, and thus rock the transverse shaft to which the same is secured. This movement operates, through the described connections, to rock the longitudinal shafts 106 and 112, and thereby open one of the blow-molds and close the other, the arrangement being such that the blow-mold at the outer end of the machine is opened and the inner mold, which then stands at the center of the machine, is closed about the blank under the plunger.

Each of the blow-molds is preferably provided with a tilting bottom 129, Figs. 2 and 25, pivoted in an opening in the table. To the forward or outer side of the bottom are pivoted two hook-shaped links 130, extending rearwardly at opposite sides of the tappet-arm 126. The inner ends of these links are suitably supported, as by chains 131. When the end of lever 127 has tilted the tappet-arm 126, it continues its inward movement far enough to engage and pull upon the hook-shaped links 130, thereby operating to tilt the bottom 129 of the open blow-mold and eject the finished article.

As has heretofore been stated, in the present machine the combined plunger and blowpipe is suitably connected with a supply of compressed air. For that purpose I provide a pipe 132, connected at one end to the source of supply and at the other end, by means of a flexible hose or pipe 133, with a suitable passage in the movable cross-head 19. The pipe 132 is provided with a cock or valve 134, of any suitable construction, Figs. 3, 5, and 23, for admitting and shutting off the air, such valve being operated at the proper times by mechanism preferably constructed and arranged as follows: The valve 134 is provided with opposite actuating-arms 135 and 136. Adjacent to the valve is a shaft 137, rotated by suitable means, such as by a chain 138, connecting a sprocket-wheel 139 on shaft 137 with a sprocket-wheel 140 on the cam-shaft 27, said sprocket-wheels being of equal size, so that the shaft 137 may rotate at the same speed as the cam-shaft. The shaft 137 is provided with two trip-arms arranged on opposite sides of the valve-stem and at right angles to each other, (see Fig. 23,) so that with each quarter-revolution of the shaft 137 one of its trip-arms will strike one of the valve-actuating arms and move the valve in one direction and then wipe past the valve-actuating arm. (See Fig. 22.) Such movement throws the other valve-actuat-

ing arm in the path of the other trip-arm, so as to be engaged and moved by the latter to return the valve to its former position. It will thus be seen that with each complete revolution of the cam-shaft 27 the valve is opened and closed twice.

The driving mechanism for the present machine is preferably constructed and arranged as follows: 141 represents a main driving-shaft (see Figs. 3, 4, and 5) arranged parallel with the cam-shaft 27 and counter-shaft 43 at the rear of the machine and provided with a driving-pulley 142. The shaft 141 is mounted eccentrically in a cylindrical bearing-block 143, the latter being journaled in a bearing 144, mounted on the main frame. (See Figs. 5 and 9.) By a small rotative movement of the block 143 the shaft 141 is moved toward or away from the counter-shaft 43. The shaft 141 carries a friction-wheel 145, adapted to make contact with a friction-wheel 146 on the counter-shaft 43 when the shaft 141 is moved toward said counter-shaft. The block 143 is provided with an arm 147, preferably integral therewith, the end of which is pivotally secured to the end of a rod 148. The opposite end of the rod 148 is pivotally secured to an arm 149 on the treadle-shaft 69. When the treadle is depressed by the operator, the rod 148 is drawn forward, and thereby causes a slight rotative movement of the block 143 in its bearing, which serves to throw the shaft 141 toward the counter-shaft 43, bringing the friction-wheels 145 and 146 into contact with each other and revolving the counter-shaft. The counter-shaft carries on its opposite end a pinion 150, meshing with a pinion 151 on the cam-shaft 27, whereby the latter is driven. The driving-shaft is supported at its other end 40 in a bearing 142^a, Fig. 5, which affords sufficient play to permit the movement above described.

152, Figs. 5 and 9, represents a disk secured to the cam-shaft 27 adjacent to the rod 148 and provided with two diametrically opposite notches 153 in its periphery. 154 represents a dog pivotally attached to the rod 148, the free end of which, preferably provided with a roller, is adapted to enter either of the notches 153. The dog is held yieldingly against the periphery of the disk 152 by means of a spring 155, arranged between the dog and the rod 148. When the machine has been set in motion by the depression of the treadle, as above described, the weight 71 tends to drop to elevate the treadle, and thus effect the separation of the friction-wheels 145 and 146, but cannot do so as long as the end of the dog 154 is riding on the unbroken periphery of the disk 152. When, however, one of the notches 153 on the periphery of the disk comes opposite the end of the dog, the latter enters the notch, permitting the weight to drop, the treadle to rise, and the driving-shaft 141 to 65 be thereby retracted, thus automatically stop-

ping the machine. When the treadle is again depressed, the rod 148 is drawn forwardly, whereby the end of the dog 154 is moved out of the notch 153, the friction-wheels 145 and 146 are brought into contact, and the machine again set in motion, which continues until the disk 152 has made another half-turn, bringing the other notch 153 opposite the free end of the dog.

As has already appeared from the description hereinbefore given, the plunger of the present machine is depressed by gravity, and the extent of its downward stroke is regulated by the amount of glass in the press-mold. In the use of such pressing mechanism it is practicable and of advantage to indicate to the operator the amount of glass which has been dropped into the press-mold in each case, so as to guide him in charging the press-mold for the next article. I have illustrated in Figs. 1, 3, and 4 a suitable gage mechanism and indicator for this purpose. 156 represents a dial-plate fixed to a stationary part of the machine, such as the cross-piece 26, and provided with a scale or graduation arranged in an arc on its face. 157 represents a pointer pivoted to the dial-plate concentrically with the scale or graduation. This pointer is normally held raised by a spring 158 of any suitable construction. A link 159 is pivoted at its upper end to the pointer and extends downwardly adjacent to the movable cross-head 19 of the plunger, where it terminates in a hook 160, extending beneath and in the path of a projection 161 on the said movable cross-head. When the plunger and cross-head descend, the projection 161 engages the hook 160, pulling the link and pointer downwardly during the latter portion of such downward movement, and the pointer therefore indicates on the graduated dial the extent of the downward movement of the plunger in each case.

The operation of the complete machine hereinbefore shown and described is as follows: Assuming the table to be standing at the left-hand limit of its movement, as shown in Fig. 2, with the press-mold closed beneath the left-hand cutter, the left-hand blow-mold open, a finished article in the right-hand blow-mold still under the plunger, the neck-mold open and elevated, and the machine at rest with the treadle in its elevated position, the gatherer drops a charge of molten glass through the opening in the cutter-frame into the press-mold and depresses the treadle with his foot. As the treadle descends its arm 72 strikes the depending arm 74 of lever 73, elevating the latter and through the described connections moving the blades of the cutter inwardly to cut off the gather. The weight on the lever 73 immediately thereafter serves to return the latter and the cutter-blades to their normal position. The downward movement of the treadle being continued, the shaft 69 is 130

rocked and the rod 148 drawn forwardly, thus disengaging the dog 154 from the notch in the disk 152 and throwing the friction-wheel 145 on driving-shaft 141 into contact with the friction-wheel 146 on counter-shaft 43. Motion is then transmitted to the counter-shaft and therefrom by the pinions 150 and 151 to the cam-shaft 27. The rotation of the cam-shaft 27 now causes the end of the depending 5 stud 32 of the table 3 to travel in the upper oblique track on the back of the drum 28, Fig. 2, and thereby moves the table longitudinally to the right until the press-mold has come under the plunger, where the movement of the table is arrested, while the stud 32 is traversing the intermediate straight track 30. As soon as the press-mold has arrived in position under the plunger the neck-mold cam, Fig. 12, draws the levers 102 toward each 10 other, and these levers through the described connections operate to first close the neck-mold sections and then lower the same bodily upon the press-mold. Just as this has been accomplished the rear end of one of the circumferential portions 46 of the cam 45, Fig. 10, passes the end of the arm 44, and thereby permits the weighted arm of lever 33 to drop, whereby the plunger is impelled into the glass in the press-mold and the blank pressed. 15 After a sufficient dwell one of the radial portions 47 of cam 45 engages the end of arm 44, forcing the same outwardly upon the other circumferential flange, and thereby elevating the weighted arm and the plunger. The drum 28 continuing to revolve and the end of the intermediate straight portion 30 of the cam-track having almost reached the stud 32, the opposite projections 104 on the drum, Fig. 3, engage the lower ends of levers 105, rocking 20 the bell-crank levers 107 and through the described connections drawing the press-mold sections apart, the pressed blank being left suspended from the neck-mold under the plunger and in the path of the blow-mold, which is now advanced. The end of the intermediate straight portion of the cam-track has now passed the stud 32, and the revolution of the drum 28 still continuing the said stud traverses the next oblique portion until it reaches 25 the end straight portion opposite that from which it started, and the table has thereby been moved another step to bring the open left-hand blow-mold to the center of the machine. By the same movement of the table the press-mold has been carried to its other charging position at the right of the plunger and has been gradually closed by the ends of the depending arms 108 of levers 107, running in the curved grooves 116 of cam-plate 114, 30 as already explained. The table has now reached the right-hand limit of its movement, and the right-hand cam-disk 128 operates its lever 127 to throw the upper end of the same inwardly against the tappet-arm 126 of transverse shaft 118^a. The consequent oscillation

of shaft 118^a operates through the described connections to oscillate the upper longitudinal shafts 112, so as to close the left-hand blow-mold about the pressed blank under the plunger and to open the right-hand blow-mold at the end of the machine to discharge its finished article, the pivoted bottom of said mold being tilted for that purpose, as already described. As soon as the left-hand blow-mold has been closed about the blank one of the trip- 70 arms on the shaft 137 operates one of the actuating-arms of the valve 134 to open the same and air is forced through the supply-pipe, flexible hose, cross-head, and plunger into the suspended blank and the body of the latter blown 75 out to the form defined by the inner walls of the blow-mold. The portions 98 of the neck-mold cam, Fig. 12, then engage the rollers on the levers 102 to draw the same apart, whereby the neck-mold sections are first opened 80 and then lifted bodily from off the neck-mold. One of the notches 153 in the periphery of disk 152 has now come opposite the end of dog 154 and the weight 71 has operated to throw the dog into the notch, thereby automatically stopping the machine with the air being still blown through the plunger into the finished article in the blow-mold. The passage of the air into the article is continued 85 until the machine is started again, since I have found this to be of advantage in properly cooling the article. Just as the table was completing its last movement to the right the projection 58 on its edge at its left-hand end had engaged the depending arm of bell-crank 90 lever 57 and through the described connections with the rock-shafts 52 and 52^a had oscillated the latter to raise the left-hand cutter-frame and to simultaneously lower the right-hand cutter-frame to its operative position immediately over the press-mold. The machine having now stopped, the gatherer drops a charge 95 of molten glass into the press-mold standing at the right of the plunger and then depresses the treadle to first operate the right-hand cutter 100 and then again starts the machine. As the machine starts the air-valve is immediately closed and the table is then moved in the reverse direction to carry first the press-mold and then the right-hand blow-mold into position under 105 the plunger, the same series of operations being performed as before.

As stated at the outset of this specification, I have herein illustrated and described a complete machine in the form which I regard as 110 the preferable embodiment of my invention in all its features. It is, however, obvious that the specific mechanism of this machine may be altered in many respects without materially changing its general organization and operation, and it is also obvious that certain features of my invention may be employed in machines of other types.

What I claim, and desire to secure by Letters Patent, is—

1. In a machine for the manufacture of glass-ware, the combination with a blank-support adapted to retain a glass blank in the path of movement of an approaching finishing-mold, 5 of a movable mold-support, a blank-mold and a finishing-mold mounted on the mold-support, and means for moving the mold-support to carry first the blank-mold and then the finishing-mold into operative relation with the blank-support, substantially as described. 10
2. In a machine for the manufacture of glass-ware, the combination with a movable mold-support, a blank-mold and a sectional finishing-mold mounted on the mold-support, and 15 means for moving the mold-support intermittently, of means for disengaging the blank-mold from the glass blank, a blank-support adapted to retain the blank in the path of the approaching finishing-mold, and means for closing the finishing-mold around the blank, 20 substantially as described. 85
3. In a machine for the manufacture of glass-ware, the combination with a movable mold-support, a sectional blank-mold and a sectional 25 finishing-mold mounted on the mold-support, and means for moving the mold-support intermittently, of a sectional neck-mold, means for closing the neck-mold upon the blank-mold, means for opening the blank-mold to 30 disengage the glass blank, and means for closing the finishing-mold around the blank while the latter is held by the neck-mold, substantially as described. 95
4. In a machine for the manufacture of glass-ware, the combination with an internal forming member adapted to shape the glass by 35 two successive operations, of a movable mold-support, a blank-mold and a finishing-mold mounted on the mold-support, and means for 40 moving the mold-support to carry first the blank-mold and then the finishing-mold into position to coöperate with the internal forming member, substantially as described. 100
5. In a machine for the manufacture of glass-ware, the combination with an internal forming member adapted to shape the glass by 45 two successive operations, of a movable mold-support, a blank-mold and a finishing-mold mounted on the mold-support, means for moving the mold-support to carry first the blank-mold and then the finishing-mold into position 50 to coöperate with the internal forming member, and a blank-support adapted to retain the glass blank at the operating-point in the path of the approaching finishing-mold, substantially as described. 115
6. In a machine for the manufacture of glass-ware, the combination with a pressing and blowing member, of a movable mold-support, 60 a press-mold and a sectional blow-mold mounted on the mold-support, means for moving the mold-support intermittently to carry the said molds successively into position to coöperate with said pressing and blowing member, 65 means for disengaging the press-mold from the glass blank, a blank-support adapted to retain the blank at the operating-point in the path of the approaching blow-mold, means for closing the blow-mold around the blank, and means for disengaging the blank-support 70 from the blank, substantially as described. 120
7. In a machine for the manufacture of glass-ware, the combination with a pressing and blowing member, of a movable mold-support, a sectional press-mold and a sectional blow-mold mounted on the mold-support, means for moving the mold-support intermittently to carry first the press-mold and then the blow-mold into position to coöperate with the pressing and blowing member, a sectional 75 neck-mold, means for closing the neck-mold upon the press-mold, means for opening the press-mold to disengage the glass blank, means for closing the blow-mold around the blank, and means for opening the neck-mold to disengage the neck of the article, substantially as described. 85
8. In a machine for the manufacture of glass-ware, a blank-mold, a plurality of finishing-molds, and means for moving the blank-mold 90 alternately with each of the finishing-molds to a common operating-point, substantially as described. 95
9. In a machine for the manufacture of glass-ware, the combination with a pressing and blowing member, of a press-mold, two blow-molds, and means for moving the press-mold alternately with each of the blow-molds into position to coöperate with the pressing and blowing member, substantially as described. 100
10. In a machine for the manufacture of glassware, the combination of a movable mold-support, a blank-mold and a plurality of finishing-molds mounted on the mold-support, and means for moving the mold-support to carry the blank-mold alternately with each of the finishing-molds to a common operating-point, substantially as described. 105
11. In a machine for the manufacture of glassware, the combination with a pressing and blowing member, of a movable mold-support, a press-mold mounted thereon, a pair of blow-molds also mounted on the mold-support, one on each side of the press-mold, and means for reciprocating the mold-support to carry the press-mold alternately with each of the blow-molds into position to coöperate with the pressing and blowing member, substantially as described. 115
12. In a machine for the manufacture of glassware, a plunger provided with a longitudinal interior passage connected with a supply of fluid under pressure, a valve in said fluid-pressure connection, a main power-driven shaft, and mechanism operated by said main shaft for opening and closing said valve, substantially as described. 120
13. In a machine for the manufacture of glassware, the combination with a main power-driven shaft, and means for throwing 130

- 5 said shaft into and out of gear with the rest of the machine, of a blowing member, a valve controlling the admission of fluid under pressure to said blowing member, and means constructed and arranged to automatically open said valve to admit the fluid to said blowing member before the said main shaft is thrown out of gear, and to close said valve after the said main shaft has again been thrown into gear, whereby the said valve remains open and the fluid is supplied to said blowing member while the machine is at rest, substantially as described.
- 10 14. In a machine for the manufacture of glassware, the combination with a pressing and blowing member, a movable mold-support, and main power-driven shaft, of mechanism for depressing said member to press a blank, mechanism for admitting fluid under pressure to said member, and mechanism for moving said mold-support in alternation with the operation of said pressing mechanism and said blowing mechanism respectively, substantially as described.
- 15 15. In a machine for the manufacture of glassware, and in combination with a body-mold, a movably-supported sectional neck-mold, and a single operating mechanism for the neck-mold acting to first move the sections thereof relatively to each other, and then to move the neck-mold bodily relatively to the body-mold, substantially as described.
- 20 16. In a machine for the manufacture of glassware, and in combination with a body-mold, a sectional neck-mold, a frame supporting the neck-mold sections and movable toward and from the body-mold, and a single mechanism for opening and closing said sections and moving said frame, substantially as described.
- 25 17. In a machine for the manufacture of glassware, the combination with a main power-driven shaft, a movable mold-support, a pair of body-molds mounted on the mold-support, a sectional neck-mold supported above the line of movement of said body-molds, and mechanism operated by the main shaft for intermittently moving the mold-support to carry the said body-molds in succession to and away from said neck-mold, of mechanism also operated by said main shaft for closing said neck-mold upon one of said body-molds, holding said neck-mold closed and *in situ* during the movement of the table to bring the other body-mold thereunder, and then opening said neck-mold, substantially as described.
- 30 18. In a machine for the manufacture of glassware, the combination with a neck-mold frame, of a supporting member carried thereby and frictionally engaging a stationary portion of the machine to support the neck-mold frame at different elevations, substantially as described.
- 35 19. In a machine for the manufacture of glassware, the combination with a neck-mold frame, of a pair of plates carried thereby and yieldingly held against a stationary portion of the machine, substantially as described.
- 40 20. In a machine for the manufacture of glassware, the combination with a frictionally-supported frame, neck-mold sections carried thereby, levers pivoted to said frame and connected to said neck-mold sections, and means for operating said levers to first move said sections relatively to each other, and then move the frame bodily, substantially as described.
- 45 21. In a machine for the manufacture of glassware, the combination with a neck-mold frame having an opening therethrough for the passage of a plunger, of a plunger-ring fixed in said opening, and a plurality of neck-mold sections carried by said frame and adapted to be closed in alignment with said opening, substantially as described.
- 50 22. In a machine for the manufacture of glassware, the combination with a cutter, of a weighted lever connected to the same, and having a depending arm, and a treadle provided with an actuating-arm adapted to engage the depending arm of said weighted lever, substantially as described.
- 55 23. In a machine for the manufacture of glassware, the combination with a movable mold-support, a mold mounted thereon, and means for moving the mold-support to carry the mold into charging position, of a cutter movable toward and from the mold, and means for moving the cutter, substantially as described.
- 60 24. In a machine for the manufacture of glassware, the combination with a movable mold-support, a mold mounted thereon, and mechanism for moving the mold-support to carry the mold into charging position, of a cutter movable toward and from the mold, and mechanism operated by the movement of the mold-support for moving the cutter toward the mold as the latter comes into charging position, substantially as described.
- 65 25. In a machine for the manufacture of glassware, the combination with a movable cutter, of an operating mechanism detachably connected thereto, and means for moving the cutter into and out of connection with such operating mechanism, substantially as described.
- 70 26. In a machine for the manufacture of glassware, the combination with a movable cutter, of an operating-bar therefor, an eye in said operating-bar, and a member attached to the cutter adapted in one position of the cutter to engage in said eye, and in another position of the cutter to be out of said eye, substantially as described.
- 75 27. In a machine for the manufacture of glassware, the combination with a movable mold-support, a mold mounted thereon and mechanism for moving the mold-support to carry the mold into charging position, of a cutter movable toward and from the mold, an operating mechanism therefor which is dis-

connected from the cutter when the latter is in its retracted position, and mechanism operated by the mold-support as the mold comes into charging position for moving the cutter

5 toward the mold and for connecting the cutter with its operating mechanism, substantially as described.

28. In a machine for the manufacture of glassware, the combination with a plunger, of vertically-movable cutters arranged one on each side of the plunger, and means for elevating and lowering said cutters in reverse, substantially as described.

29. In a machine for the manufacture of glassware, the combination with a plunger, a movable mold-support, and a mold carried thereon, of vertically-movable cutters arranged one on each side of the plunger and above the line of movement of the mold, and means operated by the movement of the mold-support for elevating and lowering said cutters in reverse, substantially as described.

30. In a machine for the manufacture of glassware, the combination with a plunger, and cutters arranged one on each side thereof, of an operating mechanism common to both cutters, and a detachable connection between each cutter and said operating mechanism, substantially as described.

31. In a machine for the manufacture of glassware, the combination with a pair of cutters reversely movable into and out of operative position, of a common operating mechanism therefor, and a detachable connection between each cutter and said operating mechanism, which is closed when the cutter is in operative position and open when the cutter is out of operative position, substantially as described.

32. In a machine for the manufacture of glassware, the combination with a main power-driven shaft, of a movable mold-support, a sectional mold mounted thereon, and mechanism operated by the main shaft for moving the mold-support, of mechanism also operated by said main shaft for opening said mold, and mechanism operated by the movement of the mold-support for closing said mold, substantially as described.

33. In a machine for the manufacture of glassware, the combination with a main power-driven shaft, a plunger, and mechanism operated by said shaft for depressing and raising the plunger, of a movable mold-support, a sectional mold carried thereon, mechanism operated by said main shaft for moving the mold-support to carry the mold to and away from position to coöperate with the plunger, mechanism operated by said main shaft when

the plunger is raised to open the mold, and mechanism operated by the movement of the table to close the mold, substantially as described.

34. In a machine for the manufacture of glassware, the combination with a movable mold-support, a pair of sectional molds mounted thereon, and means for moving the mold-support, of mechanism connected to each of said molds for opening and closing them in reverse, substantially as described.

35. In a machine for the manufacture of glassware, the combination with a main power-driven shaft, of a longitudinally-reciprocating mold-support, a pair of sectional molds mounted thereon, mechanism also mounted on the mold-support for opening and closing said molds in reverse, and mechanism operated by the main shaft for reciprocating the mold-support, of mechanism arranged at the opposite limits of movement of the mold-support and operated by said main shaft, for operating said mold-operating mechanism, substantially as described.

36. In a machine for the manufacture of glassware, the combination with a sectional mold, and a support therefor, of a tilting bottom for said mold pivoted on said support, mechanism for opening the mold, mechanism for tilting the bottom, and means for successively operating said opening mechanism and said bottom-tilting mechanism, substantially as described.

37. In a machine for the manufacture of glassware, the combination with a plunger, and operating mechanism therefor which permits the length of the stroke of the plunger to be controlled by the glass in the mold, of a projection carried by the plunger, an indicator, and a movable member below and in the path of the downward movement of the projection carried by the plunger, and connected to the indicator, substantially as described.

38. In a machine for the manufacture of glassware, the combination with a plunger and operating mechanism therefor which permits the length of the stroke of the plunger to be controlled by the glass in the mold, of an indicator, and a connection between the indicator and plunger, which is operated only during the latter part of its downward stroke, substantially as described.

In testimony whereof I have hereunto set my hand.

ROBERT GOOD, JR.
